INVENTOR

UNITED STATES PATENT OFFICE.

CHARLES ELLSWORTH ADAMSON, OF MUNCIE, INDIANA.

ROTARY COPYING-PRESS.

No. 823,094.

Specification of Letters Patent.

Patented June 12, 1906.

Application filed June 9, 1904. Serial No. 211,859.

To all whom it may concern:

Be it known that I, CHARLES ELLSWORTH ADAMSON, a citizen of the United States, residing at Muncie, in the county of Delaware 5 and State of Indiana, have invented a new and useful Rotary Copying-Press, of which the following is a specification.

My invention relates to improvements in rotary copying-presses or machines that are 10 used for making press-copies of business-letters and all written documents; and the objects of my invention are to construct a simple and durable machine in which the copying-paper is carried in a roll and cut off 15 into loose sheets before the copy is made, thereby making the copies on loose sheets, the paper being cut of a length to suit each particular letter.

A further object is to arrange the machine 20 so the copy is made in full view of the operator and also to arrange the mechanism so that a letter can be given one or more impressions before removing the copy from it.

These and other objects I accomplish by 25 the mechanism illustrated in the accompanying drawings, in which—

Figure 1 is a perspective view of my machine, showing it as it appears when making 30 a copy. Fig. 2 is a longitudinal section. Fig. 3 is a front end elevation, and Figs. 4, 5, 6, 7, and 8 are detail views.

Similar letters refer to similar parts throughout the several views.

The main frame of my machine consists of 35 two side rails A A, which are made right and left, and the front cross-end C and rear end C'. The ends C and C' firmly hold the sides together by means of machine-screws a, all as shown in Figs. 1, 2, and 3. At the forward 40 end of the frame are two elevated bearing-lugs A' A', which form journal-bearings for the journal ends of the rubber copying-roller B. One of the journals of the said roller extends through a lug A', so that the crank B' is 45 secured. Directly below and parallel to the copying-roller B is a small metal bearing-roller D, journaled on the frame. (Most clearly shown in Figs. 2 and 3.) This roller is set a proper distance from the rubber roller, 50 so as to give a suitable impression or pressure to the copying-plate E, which works between them. The said plate E is made of thin metal, having two of its edges b b turned down to stiffen it. The rear end c of the said 55 plate is beveled off, forming a cutting edge for cutting the copying-paper crosswise into

sheets. Two guide ears or projections d d are formed on the rear corners of the plate. (Most clearly shown in Fig. 4.) These projections fit into a groove e, cut into the inside 60 of each side rail A. (Most clearly shown in Figs. 1, 6, and 7.) By these projections resting in the said grooves the copying-plate is supported at its rear end, allowing the said plate to move freely endwise, as is the case 65 when making a copy, and they also form a stop for the plate to prevent it from running entirely out of the rolls B and D. The grooves e extend from a point of contact between the rolls B and D to a point near the 70 rear end of the side rails, all as shown in Figs. 1, 2, and 7.

In Fig. 2 the plate is shown run back as far as it will go, showing that the forward end of the said plate is still resting between the said 75 rolls B and D and that the rear or cutting end of the plate is resting against the copying-paper and roller K.

On the inside and near the lower edge of each of the side rails A A is a rib F, which extends almost the entire length of the said rails. (Most clearly shown in Figs. 2 and 6.) On each of these ribs rests an impression-bar G, one of which is shown in Fig. 5. These bars are each formed with two journal-bearings f and g and a bearing-recess h for the ends of the impression-spring H, all as clearly shown in Fig. 5. The impression-spring H extends crosswise of the frame, each end resting in a recess h and on the rib F. In 90 each central bearing f rests one end of the journal I for carrying the roll of copying-paper, the position of which is indicated in Fig. 2. In the end bearings g the journals of the moistening-roller J are secured. (Most 95 clearly shown in Figs. 1 and 2.) The said moistening-roller is made of tubing having a cast head J' secured in each end, the outer end of each head being formed into a spindle or journal J''. (Most clearly shown in Fig. 8.) This roller is covered by having a thin linen cloth J''' wound around it and the cloth turned in at the ends of the roller into a recess formed by the heads J', being set in a short distance back from the end of the roll, 100 and after the cloth is turned into the recess it is securely held in place by a spring-ring i. (Most clearly shown in Fig. 8.) The moistening-roller J rests directly against the paper-delivery roller K, which is journaled to 105 the side rails A A just in rear of the moistening-roller, and it being much smaller than

the latter and journaled higher up on the frame it inclines to hold the moistening-roller down, bearing the bars G against the ribs F. The delivery-roller K is made the same as roller J, except much smaller in diameter and having one of its journals extending through one of the side rails to which the crank K' is secured, as shown in Fig. 1. It is also covered with cloth in the same manner as roller J. The pressure of roller J against roller K is regulated by a thumb-screw L, which is adjusted to bear against the spring H, the said screw being tapped into the end bar C near its central part, all as shown in Figs. 1, 2, and 3. The roll of copying-paper is supported in the journal I, which rests in bearings f f on the bar G, and the paper from this roll passes down under roller J and up between it and roller K, and by the adjustment of the impression-screw L the said paper can be moistened to any degree desired. It will be seen in Fig. 2 that the dampening-roller J extends down into the water-pan M, which surrounds the lower portion of said roller, and by keeping this pan sufficiently full of water to reach the roller the cloth covering will absorb and retain the moisture at all times and dampen the copying-paper as it runs around it. Just in rear of the roller K is pivoted a small thread-guide roller N. (Most clearly shown in Figs. 1, 2, and 7.) This small roller N is parallel to the roller K, and a number of heavy threads K'' encircle the two rolls K and N. (Most clearly shown in Figs. 1, 2, and 7.) These threads are for the purpose of separating the moist copying-paper O from the impression-roller K at a point where the cutting end e of the plate E comes in contact with the said paper and roller K. The threads are placed about one inch apart, and they are held in their positions by the copying-paper adhering to them and to the roller K. (Most clearly shown in Figs. 1 and 2.)

By locating the roll of copying-paper parallel to the dampening-roller and on bars G G the paper will feed around the dampening-roller freely, and in so doing it passes through the water and against the wet covering on the rollers, and the excess water is pressed out of the paper at the pressure-point between the two rolls. It will be seen in Fig. 2 that the end bars C and C' are provided with suitable lugs a', through which the machine-screws a pass to rigidly hold the frame of the machine together.

The operation of my machine is as follows: The letter to be copied is placed on the copying-plate written side up. The crank K' is then turned to the right and a moist sheet O of copying-paper is run out, as indicated by the arrows and dotted line in Fig. 2. As soon as a sufficient amount of paper is turned out to cover the written part of the letter it is stretched backward against the cutting end e

of the plate E. Then by pulling quickly to one side the sheet Q is cut off. This loose sheet Q is then laid down over the letter P, and by turning the large crank B' to the right the copy-plate E is carried under the copying-roller B, as indicated in Fig. 1. The said crank is turned to the right until the plate is run as far out as it will go, the projections d d coming in contact with the end of the grooves e e directly under the roller B. Then by reversing the crank to the left the plate is run back to its normal position, thus giving the letter two impressions, completing the copy, and resting the plate in the position shown in Fig. 2. This operation can be repeated according to the number of letters to copy, or if two or more copies are desired from the same letter the first copy is removed without disturbing the letter and the copying operation repeated for each copy desired.

When it is desired to copy a sheet written on both sides, a sheet of moist copying-paper is cut off and placed on the plate, then the letter placed over it, and another sheet of moist copying-paper placed over the letter, so that the letter is between two moist sheets, in which position it is given the copying impressions. Two or more letters may be copied at one time by placing them on the copying-plate one over the other, with a sheet of moist copying-paper in contact with the written side of each letter. This, however, is limited, as the more sheets placed on the copying-plate the harder the impression and the more power it will require to operate the copying-roller.

I do not confine myself to any particular way of fastening the cranks B' and K' or to other minor details of construction.

I do not desire to claim herein the copying device, as that has been made the subject-matter for a separate application which was filed February 10, 1905, and bears Serial No. 245,119.

What I claim as my invention, and desire to secure by Letters Patent, is—

1. In a copy-press, the combination with a water-receptacle, of a delivery-roll, a paper-supply roll, a dampening-roll beneath which the paper passes mounted over the water-receptacle, and means for holding said dampening-roll in yielding engagement with said delivery-roll.

2. In a copy-press, the combination with a water-receptacle, of a delivery-roll, a paper-supply roll, a dampening-roll mounted in movable bearings over said water-receptacle, and a spring for holding said dampening-roll in frictional engagement with said delivery-roll.

3. In a copy-press, the combination with a main frame, of a delivery-roll journaled in one end thereof, a water-receptacle within said frame, a roll-carrying frame slidably secured in said main frame, a dampening-roll

jounaled in said frame and overlying said water-receptacle, a paper-supply roll and means for adjusting said frame to bring said dampening-roll into frictional engagement 5 with said delivery-roll.

4. In a copy-press, the combination with a main frame, a delivery-roll jounaled in one end thereof, a roll-carrying frame slidably mounted in said main frame, a dampening-roll mounted in the end of said roll-carrying frame adjacent the delivery-roll, a paper-supply roll mounted in said frame in front of said dampening-roll, a water-receptacle partially surrounding said dampening-roll, and 15 means for adjusting said roll-carrying frame in said main frame.

5. In a copy-press, the combination with a main frame, of a delivery-roll jounaled in one end thereof, a roll-carrying frame slidably mounted in said main frame, a dampening-roll mounted in the end of said roll-carrying frame adjacent the delivery-roll, a paper-supply roll mounted in said roll-carrying frame in front of said dampening-roll, a water-receptacle partially surrounding said dampening-roll, a spring interposed between the front portion of said roll-carrying frame and said main frame whereby said dampening-roll will be held in yielding engagement 25 with said delivery-roll.

6. In a copy-press, a water-receptacle, a dampening-roll partially submerged therein, a paper-supply roll, a delivery-roll adapted to receive the paper from the dampening-roll in yieldable engagement therewith, and means 35 for preventing the adhesion of the paper to the delivery-roll.

7. In a copy-press, a water-receptacle, a dampening-roll partially submerged therein, a paper-supply roll, a delivery-roll adapted 40 to receive the paper from the dampening-roll in yieldable engagement therewith, and separating devices carried by the delivery-roll for preventing the adhesion of the paper thereto.

8. In a copy-press, a water-receptacle, a dampening-roll partially submerged therein, a paper-feed roll, a delivery-roll in yieldable engagement with the unsubmerged portion of said dampening-roll, a guide-roll and a plurality of flexible belts connecting said feed 45 and guide rolls.

In testimony whereof I have signed my name to this specification in the presence of two subscribing witnesses.

CHARLES ELLSWORTH ADAMSON.
